Gary P. Van Wye.

UNITED STATES PATENT OFFICE.

FREDERICK SCHLAIS, OF BROOKLYN, NEW YORK.

WINDOW HINGE.

1,417,110.

Specification of Letters Patent. Patented May 23, 1922.

Application filed July 13, 1921. Serial No. 484,311.

To all whom it may concern:

Be it known that I, FREDERICK SCHLAIS, a citizen of the United States, residing at New York, borough of Brooklyn, in the 5 county of Kings and State of New York, have invented a new and useful Window Hinge, of which the following is a specification.

This invention relates to hinges, and especially to that class used with porch windows; and the object of the invention is to provide a hinge which will permit the window to be swung outwardly for the purpose of ventilation; a further object of the invention is to provide a hinge which will permit the swinging of the window, or rather, the turning of the same for the purpose of cleaning.

The invention is illustrated in the accompanying drawing, in which—

Fig. 1, is a view of an elevation of window, partly open, showing my improved hinge applied thereto;

Fig. 2, is a sectional elevation of a window 25 swung outwardly at both top and bottom for the purpose of ventilation—my hinge at both the top and bottom being shown in full lines;

Fig. 3, is a view of an elevation of a window being turned—showing how my hinge 30 holds the same;

Fig. 4, is a sectional view, on an enlarged scale, of a portion of a window, with one of my hinges connected therewith—the 35 dotted lines indicating one of the operations possible with the hinge;

Fig. 5, is a perspective view, showing how the hinge is connected with the sash of a window; and

Fig. 6, is a perspective view of the folding part of the hinge.

In the drawing like numerals of reference refer to the same parts in each of the views.

In the practice of my invention I provide 45 a hinge proper 7, which is provided with a leaf 8, which is provided with screw holes for attaching to the window frame 9. To the sash 10, is attached a rod 11, preferably tubular in form so it can be slipped on a 50 stud 12, connected with a plate 13, connected with a shank 14, to an attaching plate 15.

The hinge proper is preferably provided with two leaves 16, and 17, and with a leaf 18, provided with a housing 19, adapted 55 to rotate, and slide along the tubular rod 11,

for reasons hereinafter described. I may also provide a swivel disc 20, having a lug 21, of the same width as the shank 14, so that when the disc 20 is rotated to bring the said lug coincident with the said shank 14, 60 the slot 22, in the housing 19, can be slipped over both the shank 14 and the lug 21, for reasons hereinafter explained.

In operation the tubular rod 11 is mounted on each end of a window sash 10. The 65 plate 8, of the hinge proper is attached to the window frame at both the top and bottom, corresponding with the two tubular rods 11 already attached, it being understood that one of the hinges proper is mounted at each 70 corner of the window sash. The two housings of the hinges proper are slipped on the top tubular rod, and the two housings of the hinges proper are slipped on the tubular rod 11 at the bottom of the window sash. 75 The sash is then closed, as shown in Figure 4, at which time the hinge at each corner will assume the position shown in full lines in Figure 4. When it is desired to push the sash outwardly for the purpose of ventilation, the housing 19 will slide along the tubular rod 11, and the leaves 16 and 17 of the hinge will operate as illustrated in Figure 4. When the sash is fully extended outwardly, as shown in Fig. 2, the leaves 16 80 and 17 will stand out straight, as will be readily understood—the housing 19 permitting of the necessary sliding and turning.

When it is desired to turn the sash around, for the purpose of washing, or other purpose, the disc 20 is rotated to bring the lug 21 thereof in line with the shank 14 of the attaching plate. When the shank 14 and lug 21 are in alignment, the housing 19 can be slipped off the end of the rod 11 by reason of the slot 22 in the housing, as will be readily understood. The housings 19 of the other hinges at the top and bottom can be readily slid backward and forth along the rod 11, to permit of the turning of the sash, 90 as shown in Fig. 3.

It will be understood that when the disc 20, is rotated to the position shown in Fig. 5, with the housing on the tubular rod, the housing will not slip off the end of the rod 105 11 by reason of the fact that the lug 21 will act as a stop.

It will thus be seen that I have provided a hinge which will permit of the moving of the sash for the purpose of ventilation; and 110

for the turning of the sash for the purpose of washing the contained glass on both sides, without removing the sash entirely from the window frame.

5. By making the rod 11, as shown, with the connecting plates at each end, an ordinary piece of pipe may be used, which may readily be cut to shape to fit within the plates 13, and will be securely held in place by the 10 studs 12.

The hinge is cheap to manufacture; and efficient in use.

I claim:

1. A hinge comprising an attaching plate, 15 a rod secured to the sash of a window, a housing adapted to slide along said rod, and a folding part interposed between said housing and said attaching plate.

2. A hinge comprising a folding part attached to a window, a transverse rod attached to the window sash, and means to attach said folding part and said rod, and means to detach said folding part and said rod.

25. 3. In a window hinge having a housing adapted to rotate on a rod and slide along the same, a rotatable disk adapted to hold said housing and rod connected, and means

to detach said housing from said rod, for the purpose set forth.

30

4. In a window hinge adapted to connect a sash with its frame, a folding part provided with a housing, a rod with which said housing is connected, and a device adapted to permit the separation of said housing and said rod, for the purpose set forth.

35

5. In a window hinge, a folding part provided with a housing, a tubular rod, an attaching plate provided with a stud adapted to enter one end of said tubular rod, and 40 a rotatable disc adapted to hold said housing and said tubular rod connected.

6. The herein-described window hinge comprising a folding part provided with an attaching leaf, a tubular rod, an attaching plate adapted to be connected with the window sash, said attaching plate being provided with a shank and said folding part being provided with a housing adapted to slip said shank, and a disc provided with a 45 lug of the same width as said shank and adapted to coincide therewith, rotatably secured to said attaching plate, for the purpose set forth.

50

Dated this 9th day of July, 1921.

FREDERICK SCHLAIS.
